ASA B. COPELAND, OF DENVER, COLORADO.

CARD GAME.

Application filed August 9, 1926. Serial No. 128,185.

My invention relates to card games and its primary object is to take advantage educationally of the enthusiasm and concentration that children, and adults as well, display when they are engaged in play, and to provide means whereby this spirit may be utilized to subconsciously teach the players while so engaged.

The means employed consists of a deck 10 of cards, hereinafter to be described, and a box or "pit" to be used as a receptacle for the cards that have been played.

The deck may consist of 32, 36, 52 or any number of cards that seems preferable, 15 and it includes, in addition to question cards hereinafter to be described, which comprise the greater portion of the deck, a "key" card and a "challenge" card.

Each of the question cards of the deck 20 bears a question, and they are numbered successively, as from "1" to "32," if the deck contains 32 question cards. The numbers not only serve to identify the answers on the key card, as explained infra, but they 25 are of additional significance since they also designate the score value of the cards, as will hereinafter be more fully explained.

The "challenge card" is so designated and 30 may also contain a statement to the effect that an answer to a question is challenged. This card is preferably of a color distinctly different from the other cards. Where the background of the question cards is white, it is desirable to have the challenge card 35 red, thus making it easily distinguishable from the remaining cards used in my game.

The key card contains the answers to the 40 questions on the numbered cards, and the answers are numbered to correspond with the numbers on the question cards. Thus 45 the answers to the questions on all the cards in the deck, may be readily ascertained by reference to the key card.

Referring to the drawings, which illustrate 45 an embodiment of the invention, and in which like reference characters indicate corresponding parts throughout the several views,

Figures 1 and 2 represent face views of 50 two of the question cards made in accordance with my invention;

55 Figure 5, a perspective view of the box or "pit."

Referring more specifically to the drawings, 5 represents the question cards, which comprise the greater portion of the deck. The question cards bear numbers as indicated at 6, and questions as indicated at 7. The numbers are preferably placed above the questions and prominently displayed.

While the questions illustrated pertain to Biblical history, my invention is by no means limited to this field, for it may be applied to literature, art, other branches of history and science, in fact to any field of human learning. Moreover, several decks 65 may be made up from a single field, thus 70 enlarging the scope of the application of the invention.

The remaining cards of the deck are the key card indicated at 13 and the challenge card indicated at 14. The former bears the 75 caption, "key card" or other suitable designation, and contains numbers 8 which correspond with the numbers 6 on the question cards. Opposite the numbers are the answers 9 to the questions on the question 80 cards. For instance, opposite figure "1" on the key card is the answer to the question on number "1" question card.

The "challenge card" is so designated at the top and it may carry a suitable statement such as "I challenge the answer to this question," as shown at 10.

A box or "pit" 12 is provided for the cards that have been played. However, any suitable dish or box will suffice.

In playing the game two or more persons may play, but it is more interesting when four or more persons play. A director is 90 advisable, which may be a player, or a disinterested person.

The object of the game is to answer the 95 questions without the aid of the key card, which is held by the director.

The cards are shuffled by the director, and he deals two to each player, thus giving the 100 players an opportunity to study some of the questions before having to answer any of them. The director places the remainder of the deck in a pile, face downward, on the table before the players, with the challenge 105 card beside the pile.

The player immediately to the left of the director then draws a card from the top of the pile and reads the question aloud. He now has his choice between answering and 110 challenging. If he answers and his answer is correct, he is given credit for a number of points corresponding with the number on the question card. Thus, if he correctly answers the question on card No. 19, he receives 19 points. The director keeps the score on any suitable score sheet.

If his answer is incorrect, he gets no credit and the card is placed face downward at the bottom of the pile of undealt cards, to be drawn later in the game.

- 10 If, on the other hand, he chooses to challenge he has a chance to get the credit on this card gratuitously (without answering the question) provided his challenge has not been met successfully by any other player before his next turn comes to play. He makes his challenge by putting one of his question cards in the place of the challenge card which he takes and holds until some other player has successfully met his challenge by answering correctly and receiving the credit, or until all the other players have failed to meet his challenge successfully and he can therefore claim the gratuitous credit.

This move by the challenger, of lifting and holding the challenge card and putting in its place a question card, is a challenge to any subsequent player (while the challenge card still remains in the hands of the challenger) to answer the question and receive the credit, thus meeting the challenge and depriving the challenger of his prospective gratuitous credit. If a subsequent player does thus successfully meet the challenge, the challenger at once surrenders to him the challenge card which entitles him to make a challenge at once if he so desires, but if not he returns the challenge card to its original place on the table, thus making it available for any other player who in regular order desires to make a challenge.

When the first player has either answered or challenged, the second player takes his turn at the game. If the challenge card is still in its place on the table beside the pile, there is no open challenge to be met, and he draws a question card and continues the game as it was played by the first player.

But if at any stage of the game the challenge card is in the hand of any player the next player must either decline or accept the challenge. If he declines he so announces and thus forfeits his play for this round and gets no credit and the challenge passes to the next player; but if he accepts, he lifts the question card of the challenger, reads the question aloud and makes his answer. If his answer is correct he gets his credit, the question card goes to the pit and the challenger concedes the loss of his gratuitous credit by surrendering the challenge card to the player who has thus successfully answered the challenge, as already stated.

If, however, the second player's attempt to meet the challenge is an incorrect answer he gets no credit and the challenge which is still open goes to the next player, and the game continues until all the question cards are in the pit.

It is quite apparent that the method of playing the game may be varied without departing from the spirit of the invention, as defined in the hereunto appended claims.

Having thus described my invention what I claim and desire to secure by Letters Patent is:—

1. A set of playing cards comprising a series of cards, each containing a number and a question, a card containing the answers to the questions and a challenge card.

2. An outfit for playing a card game comprising a series of playing cards, each card bearing a number and a question, a challenge card, a card containing the answers to the questions, and a box to be used as a receptacle for the cards.

In testimony whereof I have affixed my signature.
